UNITED STATES PATENT OFFICE.

ALFRED C. GILBERT, OF NEW HAVEN, CONNECTICUT, ASSIGNOR TO THE A. C. GILBERT COMPANY, OF NEW HAVEN, CONNECTICUT, A CORPORATION OF CONNECTICUT.

TOY BUILDING CONSTRUCTION.

1,270,812.

Specification of Letters Patent.

Patented July 2, 1918.

Application filed December 18, 1915. Serial No. 67,613.

To all whom it may concern:

Be it known that I, ALFRED C. GILBERT, a citizen of the United States, residing in the city and county of New Haven and State of Connecticut, have invented certain new and useful Improvements in Toy Building Construction, of which the following is a full, clear, and exact description.

This invention relates to toy building construction, and more particularly to toy blocks or bricks, and means for holding them in assembled relation so that brick houses and other buildings and structures of toy masonry can be constructed in a secure and permanent manner. The small building blocks or bricks are preferably made of sheet metal in such a manner as to simulate the bricks or blocks used in large buildings, and they may be secured in a suitable frame or frames so as to present one or more permanent walls. In some cases, the toy bricks or blocks may be used as a facing for a metal frame simulating the steel framework of a modern fireproof building, and as the toy masonry can be used to build structures which are readily portable, a toy of considerable value is provided, particularly as the character, shape and dimensions of the structures may be very widely varied according to the wishes and ingenuity of the builder.

To these and other ends, the invention consists in the novel features and combinations of parts to be hereinafter described and claimed.

In the accompanying drawings,

Figure 1 is an end elevation of a toy house embodying my improvements, with the roof and certain other parts omitted in order to show the construction;

Fig. 2 is a side view of the building shown in Fig. 1, showing the skeleton framework;

Fig. 3 is a bottom view of the building;

Fig. 3^a is a detail of the connection between the sill members;

Fig. 4 is an inside view of one of the walls;

Fig. 5 is an enlarged section on line 5—5 of Fig. 4;

Fig. 5^a is a detail perspective view of a window frame;

Fig. 6 comprises detail front, rear and side views of one of the sill members;

Fig. 7 is a detail perspective view of one of the toy bricks or blocks;

Fig. 8 shows the blank from which such a brick or block is constructed;

Fig. 9 is a perspective view of a half brick; and

Fig. 10 is a considerably enlarged detail section of one of the sill members, showing the manner of fastening one of the anchoring rods therein.

In the drawings I have shown the toy masonry used as a facing for a skeleton framework, so that the wall construction simulates that of a modern fireproof building, but, in some cases, the inner skeleton framework may be omitted. However, it is usually advantageous on account of the added strength and rigidity which it provides. I shall proceed to describe the various details of the particular construction selected for illustration, with the understanding that many features can be changed or altogether omitted without departure from the principle of my invention.

The building selected for illustration is square, and it comprises a skeleton framework built up from the strips shown in my application, Serial No. 814,533, filed January 26, 1914, although strips of other kinds may be used if desired. Referring particularly to Fig. 2, the framework at each side of the building comprises upper and lower horizontal strips 20 and upright strips 21. The strips 20, 21 are arranged to form a square, with their ends overlapped, and the overlapping ends of adjacent strips are interconnected by means of bolts 22. Each side frame composed of the strips 20, 21 is suitably connected at right angles with the adjacent side frames at either end thereof, and in the particular construction illustrated this is effected by means of angle plates 23 at the corners of the structures, said angle plates being secured by the bolts 22. Thus, each bolt 22 holds together a strip 20 and a strip 21, and also secures the side frame including said strips, to the adjacent side frame by means of one of the angle plates. In this way, a simple but strong and rigid framework for the masonry is provided.

Applied to the lower part of the framework are suitable sill members 24 which serve as a support for the toy masonry. These sill members are preferably clamped along the lower edges of the lower strips 20. Preferably, each sill member 24 is bolted to the corresponding lower frame member 20.

2 by means of bolts 25 and washers 26, said bolts passing through the lattice work of the strip in the manner shown in Fig. 2 so as to clamp the sill securely against displacement. 5 The sill member is preferably constructed of sheet metal in the particular form shown in detail in Fig. 6. It comprises a plate or body portion 27 having inwardly turned flanges 28 along the margins thereof. The 10 front of the sill is provided with a longitudinal series of equidistant perforations 29 of a size to accommodate the bolts 25. A considerable number of the perforations 29 is provided so that the fastening bolts may be 15 placed in any of a large number of different positions. The flanges 28 of the channeled sill are likewise perforated, being provided with a longitudinal series of perforations 30. These perforations 30 are of special outline, 20 as hereinafter described, and they are in staggered relation to the perforations 29. In this manner, anchoring rods 31 for holding the toy bricks in place may be held in any of the perforations 30 without interfering 25 with the passage of fastening screws through any of the perforations 29. In order to assist in locating the sill member of U-shaped cross-section properly on the framework, that flange 28 which is uppermost 30 may engage in the nicks of the heads of the lowermost bolts 22 at that side of the frame.

Preferably, the flanges 28 are of less depth than the body portion 27 of the sill, but at 35 one end an integral flange or extension 32 on the sill blank which is bent inward at right angles between the flanges is of the same depth as the outer face of the sill so as to make the sill perfectly square at the end, as 40 shown, for example, at the lower left hand corner of Fig. 2. At the other end of the sill, the latter is of forked shape, the flanges 28 being narrowed as shown at 28^a, and a square extension 27^a on part 27 being bent 45 inward between the flanges 28. In order to secure two of the sill members end to end, the square end of one member is inserted into the forked end of the other member, and said members are then suitably interlocked. 50 In Fig. 3^a, I show two sill members secured together at right angles to each other by means of one of the rods 31. This rod passes through openings 30 in the plates 28^a and through registering perforations 30 in 55 the end portion of the member which is straddled by said plates. The deep end flange 32 completely fills in and finishes off the joint, being as deep as the length of the plates or extensions 28^a, and thus a good 60 finish is produced at the corners in spite of the comparatively small amount of metal in the shallow flanges 28.

After the sill members 24 on the lower part of the framework have been interconnected 65 at the ends by upright rods 31 lo-

cated at the corners of the structure, additional rods 31 are then secured in the sill members by engaging the remaining perforations 30 in the side flanges. In order that each rod 31 may be locked in the sill, 70 said rod is provided near its lower extremity with small, diametrically located wings 31^a. As the rod is inserted through one of the upper perforations 30 of the sill, the wings 31^a pass through diametrically located cut-away portions 30^a in the edge of the perforation, after which the rod is turned so that the wings 31^a rest on the lower flange of the sill, as shown in Fig. 10, and will not 75 pass through the perforation 30 engaged by the lower extremity of the rod. By this construction, the several rods can be firmly secured against vertical displacement in the sills with either flange of the sill located uppermost, it being understood that the 80 perforations 30, 30^a of one flange are identical with those of the other.

The upright rods 31 serve as anchoring devices for a plurality of toy bricks or blocks 33. These bricks or blocks are preferably constructed of sheet metal bent up into hollow box-like form, said blocks being open at the rear. In the case of a full sized block, the upper and lower walls are provided with two perforations 34 to engage two adjacent anchoring rods. Preferably, the blocks are constructed from a sheet metal blank 35 (Fig. 8) bent into shape to present a flat rectangular outer wall 36, with top and bottom flanges 37, and end flanges 38 and 39. The perforations 34 previously mentioned are pierced through the flanges 37. The flanges 37, 38 are of a depth which is less than the width of the surface 36, but the flange 39 is square so as to make the block square at at least one end. In this manner, a building can be properly finished off at the corners without any gaps (as shown more particularly at the left of Fig. 1) in spite of the fact that the flanges 37, 38 are comparatively shallow. Half bricks or blocks 40, such as shown in Fig. 9, are generally similar to the blocks 33, but are adapted to engage only a single anchoring rod. In this case, the upper and lower flanges of the block are each provided with a single rod-engaging perforation 41.

In building up a wall, the blocks are passed over the upper free ends of the rods 31 in such a manner that a row of blocks will be laid along the sill, as shown, for example, at the lower part of Fig. 1. In the example illustrated, the lower course of blocks consists entirely of the full length blocks 33, each of which is passed over two of the anchoring rods or wires. In this manner, each block is firmly held against dislocation, either laterally or longitudinally. The blocks of the second course are staggered with respect to those of the first 130

course, and so on, as usual in brick-laying. After the blocks have been laid to a certain height, a sill 24 may be laid on the top course, said sill being passed over the 5 smooth upper ends of the rods or wires which engage the perforations 30.

In the example selected for illustration, the building is intended to have a sloping roof, and after the four walls have been 10 built up to the roof level the sill members 24 are laid on top of the four walls and interconnected with each other in substantially the same manner hereinbefore described. In this way, each wall consists of 15 a lower sill, a plurality of upright anchoring rods supported thereby, a plurality of blocks passing over and held on said rods, and an upper sill member held on the rods on top of the blocks, but in many cases the 20 upper sill member can be dispensed with.

In Figs. 1 and 5^a, I have shown a window frame 42 which may be built in with the bricks or blocks if desired. This frame is stamped up from a suitable sheet metal 25 blank and is provided with perforated lugs 43 for engaging certain of the rods 31 so that the frame may be firmly held in place. So far as structural features go, the window frame is of substantially the same character 30 as one of the blocks, as it is fastened in the wall in the same way. Other building elements, such as doors and the like can also be assembled and held in the wall in substantially the same manner herein described. Of course, it is not necessary to 35 make all of the full length bricks 33 with a square end 39, as shown in Fig. 7. It is only necessary to furnish enough of these particular blocks to finish off the corners 40 of the building, the other blocks having short flanges at both ends.

Various changes in the details of the construction may be adopted without departing from the scope of the invention as defined in the claims.

What I claim is:—

1. In toy building construction, the combination of a hollow elongated sill member of U-shaped cross-section, a plurality of upright anchoring rods secured therein, and blocks laid on said sill member and having means engaging said anchoring rods; substantially as described.

2. In toy building construction, the combination of a channeled sill horizontally arranged with one of its side flanges lowermost, a plurality of upright anchoring rods, extending downward through the other side flange of said channeled sill, and blocks laid in courses on said sill and having perforations engaging said anchoring rods; substantially as described.

3. In toy building construction, a channeled sill member constructed of sheet metal 65 and having a longitudinal series of perfora-

tions in each of the side flanges thereof, and anchoring rods engaging certain of said perforations so that said rods are sustained from beneath by said sill; substantially as described.

4. In toy building construction, a skeleton framework, a plurality of upright anchoring rods applied to the outside of said framework, and building blocks laid in courses on the outside of said framework, and having means engaging said anchoring rods; substantially as described.

5. In toy building construction, the combination of a skeleton framework, upper and lower sill members applied to the outside of said framework, anchoring rods secured in and extending between said sill members, and blocks mounted on said rods; substantially as described.

6. In toy building construction, the combination of a skeleton framework, sill members applied to the lower part thereof, said sill members of channeled cross-section and having perforations through the intermediate portion thereof, bolts passing through said perforations and securing said sill members to said framework, the flanges of said sill members provided with perforations, anchoring rods engaging said last-named perforations, and blocks laid in courses on the outside of the framework and having perforations engaged by said anchoring rods; substantially as described.

7. In toy building construction, a sill member having a plurality of horizontal perforations extending therethrough from front to rear, and a plurality of vertical rod sockets interposed between said perforations; substantially as described.

8. In toy building construction, a skeleton framework, a sill member having horizontal perforations extending therethrough from front to rear, bolts engaging said perforations and locking the sill member to said framework, said sill member having a plurality of vertical sockets, anchoring rods sustained at their lower ends in said sockets, and blocks laid in courses on the sill and having means engaging said anchoring rods; substantially as described.

9. In toy building construction, a channeled member constructed of sheet metal and having a longitudinal series of perforations through the intermediate portion thereof, a longitudinal series of perforations through the side flanges of said sill member and arranged in staggered relation with respect to said first perforations, each perforation of one of said side flanges being in line with a perforation of the other side flange; substantially as described.

10. In toy building construction, a sheet metal channel member forked at one end and squared off at the opposite end; substantially as described.

11. A toy building block constructed from a single sheet metal blank, and having top, bottom and end walls bent inward from the front wall at right angles thereto, each of 5 the top and bottom walls being provided with a plurality of perforations located at different points in the length of the block, the perforations of the top wall being in registry with those of the bottom wall; substantially 10 as described.
12. A toy building block constructed from a single sheet metal blank and having top, bottom and end walls bent inward from the front wall at right angles thereto, each of 15 the top and bottom walls being provided with a plurality of perforations located at different points in the length thereof, and said block being open at the rear; substantially 20 as described.
13. A toy building block having front, top, bottom and end walls constructed from a single blank of sheet metal, said block being open at the rear and one of the end walls extending farther back than the other 25 end wall and the top and bottom walls; substantially as described.
14. In a toy building construction, the combination of a sill, a plurality of upright anchoring rods extending upward therefrom, and a plurality of blocks laid on said sill, each of said blocks being constructed of 30 a sheet metal blank having top and bottom walls bent inward from the front wall at right angles thereto, each of said top and 35 bottom walls of the block having perforations engaging a plurality of said anchoring rods at different points in the length of the block, and said blocks being open at the rear; substantially as described.
15. In toy building construction, a channeled sill having a perforation in one of the side flanges thereof, said perforation having a cut-away portion in the edge thereof, and an anchoring rod having a lateral projection or wing adjacent one end thereof, said rod adapted to pass through said perforation when said projection or wing is in registry with said cut-away portion; substantially 40 as described.
16. In toy building construction, a side frame comprising four strips arranged to form a rectangle and having their adjacent ends overlapped, bolts interconnecting said strips at their overlapped ends, a second 45 side frame similarly constructed and disposed at a right angle to said first frame, and angle members interconnecting said 50

frames and clamped in place by the bolts which interconnect the strips of the individual frames; substantially as described. 60

17. In toy building construction, the combination of an elongated hollow sheet metal sill member having a longitudinal series of sockets therein, a plurality of anchoring rods engaging said sockets, and hollow sheet 65 metal blocks laid on said sill in courses and having rearwardly turned flanges with perforations engaging said anchoring rods; substantially as described.

18. In toy building construction, the combination of a channel member having a bifurcated end, a second channel member engaged in the bifurcated end portion of the first channel member and straddled thereby, and means for securing said two members 75 together; substantially as described.

19. In toy building construction, a skeleton framework, building blocks laid in courses on the outside of said framework, and anchoring rods on the outside of the 80 framework extending through the blocks for holding the same in place; substantially as described.

20. In toy building construction, a skeleton framework, a plurality of anchoring 85 rods applied to the outside of said framework, and sheathing means held in place by the anchoring rods; substantially as described.

21. In toy building construction, a sheet 90 metal channel member having a longitudinal row of perforations in each of the side flanges thereof, each perforation of one flange registering with a perforation of the other flange, and a central longitudinal row 95 of perforations in the intermediate or body portion of said member, the perforations of said last row being arranged in staggered relation to those of the other rows; substantially as described. 100

22. In toy building construction, a sheet metal channel member having a forked end with perforations in the opposite sides of the fork; substantially as described.

23. In toy building construction, a sheet 105 metal channel member having a forked end, a second sheet metal channel member arranged at right angles to the first and straddled by said forked end, and means for securing said two members together; substantially as described.

In witness whereof, I have hereunto set my hand on the 11th day of December, 1915.

ALFRED C. GILBERT.
